Attorney

UNITED STATES PATENT OFFICE.

EDWARD HATELEY HUGHES, OF CANTON, OHIO.

AERIAL TORPEDO.

1,269,185.

Specification of Letters Patent. Patented June 11, 1918.

Application filed July 6, 1917. Serial No. 178,983.

To all whom it may concern:

Be it known that I, EDWARD HATELEY HUGHES, a subject of the King of England, and resident of Canton, in the county of Stark and State of Ohio, have invented certain new and useful Improvements in Aerial Torpedoes, of which the following is a specification.

This invention relates to improvements in explosive projectiles; the dominant object of the invention being to provide an aerial torpedo which when discharged from a projector will plane through the air into engagement with an object and then explode; motive means being provided to drive the same through the air at a high velocity, thus, insuring accurate and steady flight thereof.

Among other aims and objects of the invention may be recited the provision of a torpedo of the character mentioned with a view to compactness, and in which the number of parts are few, the construction simple, the cost of production comparatively small, and efficiency and operation high.

Other objects will be in part obvious and in part pointed out hereinafter.

The foregoing together with additional advantageous details and arrangement of parts of the preferred embodiment of my invention will be clear from the specific description hereinafter contained, when read in connection with the accompanying drawings forming part thereof wherein said embodiment of the invention is illustrative for the purpose of facilitating a full understanding of the present improvements.

In the drawings:

Figure 1 is a perspective of the improved aerial torpedo; and

Fig. 2 is a vertical longitudinal section therethrough showing the same arranged in a projector.

Referring now more particularly to the drawings and in connection with which like reference characters will refer to corresponding parts throughout the several views, 1 designates the explosive shell, this shell having a detonating charge arranged in the forward portion thereof and adapted to be fired through the medium of a firing pin 2 which is also arranged in the forward tapered portion of the said shell.

Supporting bars 3 are arranged transversely of the shell 1 in proximity of the forward and rear portions thereof and have secured to their opposite extremities, housings

designated 4, the forward portions of which are tapered and have extending therefrom power shafts carrying propellers 5. Within the housings 4 and connected to the power shafts are compressed air motors of the conventional construction, a reservoir being also included in the arrangement within the housings in order that motive power may be supplied the motors. It is of course to be understood, that suitable means are provided and are adapted to manually or automatically control the passage of air to the compressed air motor upon the discharge of the torpedo from a projector.

Oppositely disposed pairs of vertical standards 6 are secured to the outer sides of the rearward and forward portions of the several housings 4 and carry upon their upper and lower ends air planes 7, it being noted in this connection, that the forward vertical standards are of a length greater than the rear standards, thus, causing a greater gap between the forward air planes as is between the rear air planes.

A projector 8 is provided and is supported upon a suitable mounting 9 at a slight elevation in order that the explosive shell 1 may be inserted therein, oppositely disposed slots or guides being formed in the respective sides of the projector barrel to permit the passage of the bars 3 therethrough.

When discharged from the projector the aerial torpedo will, due to the biplane structure thereof be caused to travel accurately and steadily through the air into engagement with the object at which it is discharged. Upon striking the object, the firing pin 2 will be depressed thus exploding the detonating charge in the shell.

Manifestly, the construction shown is capable of considerable modification and such modification as is within the scope of my claims, I consider within the spirit of my invention.

I claim:

1. An aerial torpedo including an explosive shell, motive means arranged upon the opposite sides of said shell, supporting means secured to the forward and rear portions of the motive means, and air planes carried upon the extremities of said supporting means and arranged in spaced relation to the motive means and shell.

2. An aerial torpedo including an explosive shell, supporting bars extending transversely to the forward and rear portions of

2
said shell, motive means arranged upon the opposite ends of said supporting bars, pairs of vertical standards secured to the forward and rear portions of the motive means, and 5 air planes carried upon the extremities of said standards and arranged in spaced relation to the motive means and shell.

3. An aerial torpedo, including an explosive shell, supporting bars arranged transversely of the forward and rear portions of 10

the said shell, motive means arranged upon the opposite ends of the supporting bars, vertical standards secured to the forward and rear portions of the motive means, certain of said standards being of greater 15 length than others, and air planes secured to the ends of said standards.

In testimony whereof, I affix my signature hereto.

EDWARD HATELEY HUGHES.
